UNITED STATES PATENT OFFICE.

ADOLPH CROFTON PECK, OF SANDUSKY, OHIO.

SHIELDING FOR RADIO APPARATUS.

Application filed September 9, 1927. Serial No. 218,519.

The present invention relates to an improved shield construction primarily intended for use in connection with radio receiving apparatus.

In radio receiving apparatus employing multiple stages of amplification at radio frequency, it is essential that the individual stages be so isolated as to prevent electromagnetic coupling between the units or 10 stages, other than through their proper channels. With the usual method now employed for shielding, a solid metal sheet is used, and this form of shielding acts as a distributing agent with the result in interference being 15 nearly as great as if no shielding were used. This solid metal sheet conductor when used as a shield in radio receiving circuits, adds a great amount of resistance to the receiver as a whole, where the tuning inductances and 20 condensers come in close contact to the shielding, and resulting in the capacity of the receiver being reduced to a point where in some cases, an extra stage or unit of amplification is required to compensate for the 25 losses so incurred. Currents generated at radio frequency will penetrate any substance with the exception of metal, and as certain metals have higher conductivity than others, the quantity of metal employed in 30 the usual sheet metal shields, together with its properties as a conductor for high frequency current, will naturally determine the amount of resistance added to the receiver when using a metal shield. When using a 35 solid sheet metal conductor for shielding purposes, it is necessary to use a fairly thick sheet in order to offset the tendency of the sheet to warp or buckle due to atmospheric changes, and which buckling or distortion 40 of the sheet causes capacity changes in the apparatus or possible short circuit due to the shielding contacting with the circuit, and both of which would tend to impair the over all efficiency of the receiving apparatus.

It is therefore a primary object of the present invention to provide an improved shield for radio apparatus embodying the operating characteristics of the solid metal shield without the inherent losses due to the employment of such solid sheet metal conductors.

A further object of the invention is to provide a novel and improved shield for radio apparatus which may be employed for either eliminating interference due to exter-

nal sources or as means to prevent interstage coupling between radio frequency units other than through their proper connecting channels.

A further object of the invention is to provide a flexible shield for radio apparatus which may be employed as a lining for the panels and cabinets that house the apparatus, in a manner whereby the signal to be received may only pass to the receiving circuit through the proper antenna binding post.

Other objects and advantages of the invention will be apparent during the course of the following detailed description, taken in connection with the accompanying drawing forming a part of this specification and in which drawing:

Figure 1 is an enlarged fragmentary plan view of the improved shield showing certain sections thereof removed and others broken away for illustrating the specific detail of construction.

Figure 2 is an enlarged fragmentary section through a section of the shield.

Figure 3 is an enlarged longitudinal section through one of the conductor leads forming a part of the shield.

Referring to the drawing in detail, and wherein similar reference characters designate corresponding parts throughout the several views, the letter A may designate as a whole, the improved shield which embodies a supporting base B, a series of conductor leads C supported by the base B, a contact base or coating D affixed to the base B as by a binder E, and F mounting means for securing the shield in adjusted relation for shielding purposes.

The base B is of a flexible nature and preferably consists of a sheet of woven fabric such as muslin of the like wove in the usual manner to form warp and woof threads 5 and 6 respectively, and the weave of the fabric is preferably like that illustrated in Figure 1 of the drawing. The fabric may of course be of either close or coarse weave for either causing the adjacent threads 5 or 6 to be either contacting one with the other or spaced a suitable distance so that relatively small openings are provided between the crossed threads. While the sheet like supporting base B has been shown as being of fabric, the same

may be formed of any sheet like material of a flexible nature and which does not constitute a conductor of electrical energy.

Referring now to the conductor leads C, the same preferably consist of strands of tinselled wire embodying a carrier thread 7 about which is spirally wound a substantially flat copper strip 8 which may either be wound with ends of adjacent convolutions in contacting engagement or slightly spaced as clearly illustrated in Figure 3. These conductor leads C are preferably woven directly into the fabric supporting base B during weaving of the fabric so that adjacent runs of the leads are suitably spaced by the warp and weft threads 5 and 6 respectively so that the leads form a substantially net like construction with the leads contacting one with another at their traversing points. Thus it will be seen that the conductor leads form an open work construction intended to be supported by the fabric B with the traversing leads in electrical contact one with another. Owing to the high electrical conductivity of copper, it is preferred that the conductor leads be so formed for reducing the absorption effect of the shield.

As in usual practice, the shield A when associated with the radio receiving set will be at a ground potential by connecting the net like construction of the conductor leads directly to a ground connection through a suitable binding post provided on the receiving apparatus.

Referring now to the contact face or coating D, the same is formed of metal fragments preferably aluminum filings. These metal fragments are intended to be affixed in a mass to one side of the fabric base B as by means of the binder E, the binder serving both as means for retaining the metal fragments in a compact arrangement and also as means for securing the coating to the supporting base. The metal fragments forming the coating D are so applied to the supporting base that the fragments are in electrical contact with one another and with certain of the metal fragments in electrical contact with the conductor leads C as is clearly illustrated in Figure 2. Thus it will be seen that the metal fragments of the coating D may be effectively grounded through the conductor leads C. Since aluminum is of low electrical conductivity in comparison to other metals such as brass and copper, it will be seen that when the shielding is placed in relatively close contact with apparatus of the receiving circuits, that loss through induction to ground will be at a minimum.

The binder E may be in the form of a gum varnish, or of a material bearing adhesive characteristics and being of a nature to exclude moisture from the fabric base B and

yet allow for the shield structure to be of a flexible nature owing to the elasticity of the binder.

It may here be well to state that the shielding A as a finished product, will resemble somewhat "emery cloth" in flexibility, and the metal fragments forming the contact face or coating may be applied to the supporting base much in the same manner as are the emery fragments applied to the cloth in manufacture of emery cloth.

It will be observed that the coating D of metal fragments, forms a sheet like covering for one face of the supporting base and forms a substantially flat surfaced coating having low conductivity and being in electrical contact with the conductor leads C which are intended to be connected with a suitable ground terminal.

As to the mounting means F, the same in the example shown is in the form of an adhesive such as gum arabic applied to the opposite surface of the supporting base B from that at which the coating D is formed. Thus it will be seen that when applying the shield for shielding purposes, the adhesive may be dampened or softened and then the shield applied permanently to the panels and sides of the cabinet of the radio apparatus. When so applying the shield, the same will form a metal barrier which entirely surrounds the receiving circuits, and by connecting the leads C with a suitable ground connection, the shield will be maintained at a ground potential. When so enclosing the receiving circuit apparatus, it will be seen that the apparatus will be effectively shielded against interfering electrostatic charges and electromagnetic waves, and that the only path through which a signal may be received and passed through the various tuning circuits, will be from the antenna directly to the antenna binding post of the receiver.

The shield may of course be used in a receiving apparatus to isolate the individual units or circuits with a minimum resistance and distributing capacity.

When so applying the shielding as by the adhesive F to the interior surface of a housing for radio receiving apparatus, it will be seen that the shield becomes permanently fixed and will not be affected by varying climatic conditions. A shielding such as disclosed may be very easily and quickly applied, since the same is capable of being readily cut by a knife or pair of shears to the exact size of the surfaces being covered by the shielding. A size of the piece of which the shielding is made may of course be of any requisite dimension in accordance with the requirements of the trade.

From the foregoing description it will be apparent that a novel and improved shield for use in connection with radio receiving

apparatus has been provided which is of a flexible sheet like nature such as to allow for ready and easy installation of the shielding, and which shield embodies novel features of construction whereby losses due to absorption and interference due to distributing effects, will be reduced to a minimum.

Various changes in the shape, size and specific materials defined may be made to the form of the invention herein shown and described, without departing from the spirit of the invention or the scope of the following claims.

15. I claim:

1. In a shield of the class described, a sheet like supporting base, a facing of fragmentitious material having electrical conductivity, affixed to said base, and a grounding conductor carried by the base and having electrical contact with the facing at spaced points throughout the area thereof.

2. In a shield of the class described, a sheet like supporting base, a net like screening having electrical conductivity, carried by said base, and a facing of fragmentitious material having electrical conductivity, affixed to said base and in electrical contact with the strands of said screening.

3. In a shield of the class described, a sheet like supporting base, a net like screening having high electrical conductivity, carried by said base, and a facing of fragmentitious material having low electrical conductivity, affixed to said base and in electrical contact with the strands of said screening.

4. In a shield of the class described, a sheet like supporting base, traversing conductor leads having electrical conductivity, supported in spaced apart relation on the base, and a facing of fragmentitious material having electrical conductivity, affixed to said base and being in electrical contact with said conductor leads throughout the area of the facing.

5. In a shield of the class described, a sheet like supporting base, a net like screening of interwoven conductor leads having electrical conductivity, supported by the base, and a facing of fragmentitious material having electrical conductivity, affixed to one face of the sheet like supporting base in electrical contact with the conductor lead of said screening.

55. 6. In a shield of the class described, a sheet like supporting base, conductor leads having electrical conductivity, interwoven in traversing relation into the supporting base with adjacent parallel leads spaced from one another, and a facing of fragmentitious material having electrical conductivity affixed to one face of the supporting base in electrical contact with said conductor leads.

65. 7. In a shield of the class described, a

flexible sheet like supporting base, a flexible grounding conductor carried by the base, and a facing of fragmentitious material having electrical conductivity, affixed to said base in electrical contact with the 70 grounding conductor and capable of being flexed with the supporting base.

8. In a shield of the class described, a flexible sheet like supporting base, a flexible net like screen having electrical conductivity, 75 carried by said base, and a flexible coating affixed to one face of the supporting base embodying metal fragments having electrical contact with said screening.

9. In a shield of the class described, a 80 flexible sheet like supporting base, a flexible net like screening having high electrical conductivity, carried by said base, and a flexible coating affixed to one side of said base embodying metal fragments of low 85 electrical conductivity, said fragments contacting one with another and being in electrical contact with said screening.

10. In a shield of the class described, a 90 flexible sheet like supporting base, a flexible net like screen having electrical conductivity, carried by said base, a flexible coating affixed to one face of the sheet like supporting base embodying metal fragments having electrical conductivity and 95 having electrical contact with said screening, and an adhesive carried by the opposite face of the sheet like supporting base from said coating.

11. In a shield of the class described, a 100 fabric sheet forming a supporting base, conductor leads interwoven into the fabric sheet in spaced apart relation, and a flexible coating affixed to the supporting base embodying metal fragments having electrical contact with said conductor leads at spaced 105 points throughout the area of the supporting base.

12. In a shield of the class described, a 110 fabric sheet forming a supporting base, conductor leads interwoven in the fabric in traversing relation and contacting one with another at their traversing points, and a facing of fragmentitious material having 115 electrical conductivity, affixed to one face of the fabric sheet in electrical contact with said conductor leads.

13. In a shield of the class described, a 120 fabric sheet embodying warp and weft threads, conductor leads interwoven in spaced relation in the fabric in parallel relation with both the warp and weft threads, a flexible coating affixed to one face of the fabric embodying metal fragments having 125 electrical contact with said conductor leads, and an adhesive affixed to the opposite face of the fabric from said coating for application of the shield for shielding purposes.

14. In a shield of the class described, a 130 fabric sheet forming a supporting base, con-

ductor leads interwoven in the fabric embodying carrier threads having spirally wound thereon strips having electrical conductivity, and a coating affixed to one face of the fabric embodying metal fragments having electrical contact with the strips of said conductor leads.

15. In a shield of the class described, a fabric sheet forming a supporting base, con-

ductor leads interwoven in the fabric sheet 10 embodying carrier threads and copper strips spirally wound about the carrier threads, and a coating affixed to one face of the fabric embodying aluminum fragments being in contact one with another and in electrical 15 contact with the strips of said conductor leads.
